UNITED STATES PATENT OFFICE.

HORACE FREEMAN, OF NIAGARA FALLS, ONTARIO, CANADA, ASSIGNOR TO AMERICAN CYANAMID COMPANY, OF NEW YORK, N. Y., A CORPORATION OF MAINE.

PROCESS OF PRODUCING SODIUM CYANID.

1,277,900.

Specification of Letters Patent. Patented Sept. 3, 1918.

Application filed April 23, 1918. Serial No. 230,363.

To all whom it may concern:

Be it known that I, HORACE FREEMAN, a subject of the King of Great Britain, residing at Niagara Falls, in the Province of Ontario and Dominion of Canada, have invented certain new and useful Improvements in Processes of Producing Sodium Cyanid; and I do hereby declare the following to be a full, clear, and exact description of the invention, 10 such as will enable others skilled in the art to which it appertains to make and use the same.

This invention relates to a process of producing sodium cyanid from lime nitrogen 15 and has for its object to improve the methods heretofore proposed.

To these ends the invention consists in the novel steps and combinations of steps constituting the process, all as will be more fully 20 hereinafter disclosed and particularly pointed out in the claims.

Referring to the accompanying drawings, forming a part of this specification, in which like numerals designate like parts in all the 25 views—

Figure 1 is a diagrammatic sectional view of a furnace suitable for carrying out this invention; and—

Fig. 2 is an enlarged sectional detail view 30 of a portion of the parts shown in Fig. 1.

1 indicates any suitable furnace preferably of the type shown, and having a base portion 2 of refractory conducting material such as carbon, 3 a lining of refractory material, and 4 an outer wall of heat insulating material. The whole is supported on any suitable foundation 5, and a suitable conductor 6 leads current to the conducting bottom. 7 is a carbon electrode dependent in a restricted crucible 9. The size of the electrode and the dimensions of the crucible are so proportioned that a slight relative motion of the fused contents of the hearth with respect to the electrodes, causes a large variation in 40 the current flowing through the furnace. The furnace is provided with a suitable tap hole 11, connected with the crucible by a passage 10 and 12 represents a bushing of iron lining said tap hole, 13 a hollow block 45 fitting said bushing; and 14 represents a

tapered iron plug carried by the rod 15, extending behind the shield 16 and adapted to be operated by an attendant.

The charge material is fed into the furnace by any suitable means, such as a hopper 55 and chute 18. It passes downward through the deep shaft of the furnace and finally melts and collects as a molten pool 21 at the bottom of the crucible.

The charge of this furnace may consist of 60 lime nitrogen, salt and calcium carbid in any suitable proportions, the mixture being dependent upon the grade of the final product to be made, and amount of attention to be given to the furnace operation. An example 65 of a suitable charge is the following:—Equal parts of lime nitrogen and salt to which is added approximately one twentieth of the weight of the mixture in ordinary calcium carbid. This said furnace charge may be 70 varied by changing the proportions of all three ingredients, but the above mixture represents an example of a practicable and economic furnace mixture. By increasing the amount of salt in proportion to the lime nitrogen used above that mentioned, one obtains a furnace mixture which can be smelted with less attention to exact operating 75 conditions than heretofore, and it is more economical under certain circumstances to 80 operate with a greater proportion of salt.

The calcium carbid may be replaced by a free carbon, preferably of such form as lamp black or similar carbonaceous material, which has not been previously heated to a 85 temperature higher than 800° C. The amount of such free carbon addition may be varied within rather wide limits but a satisfactory amount is usually about one twentieth of the weight of lime nitrogen and salt 90 in the charge.

I have discovered that when lime nitrogen as produced by the ordinary process and containing calcium cyanamid, carbon, free lime, and negligible amounts of other minor 95 impurities of no consequence, is fused with common salt a reaction takes place in stages. In the first stage, the calcium cyanamid and the sodium chlorid seem to suffer double decomposition whereby sodium cyanamid and 100

calcium chlorid is produced. This sodium cyanamid is not particularly stable and readily breaks down into other products yielding gases and vapors of various kinds.

5 If, however, chemically active carbon is present, this said sodium cyanamid will combine with the active carbon to form sodium cyanid in accordance with the following equation—

10

Now, I have found that at the temperature at which the sodium cyanamid was produced, the carbon in the lime nitrogen is still rather 15 inert and only slowly reacts with the sodium cyanamid. Rapid action of this more or less inert form of carbon seems to occur only at temperatures several hundred degrees above the formation temperature of the sodium cyanamid. There is, therefore, the possibility of having sodium cyanamid set free in the mass and in contact with only the slow 20 reacting form of carbon, thereby permitting decomposition of the sodium cyanamid with 25 a consequent foaming and violent boiling of the furnace charge.

But, by causing the reaction or fusion to take place quite rapidly the time interval between the formation of sodium cyanamid 30 at its temperature of formation and the formation of cyanid by reaction with carbon at the more favorable higher temperature may be made very short, thereby occasioning less decomposition and less foaming. In 35 other words, a rapid smelting furnace, or one using a high energy density will operate more efficiently and with less trouble than a slower melting furnace or one using a lower density on the same charge.

40 Since the quantity of sodium cyanamid in a free state at any one time may be made comparatively smaller by using the principle of rapid smelting, I have found that practically all decomposition can be avoided 45 if a very small quantity of carbon or calcium chlorid is present in the charge. Under my principle of operation where I use a high energy density and so carry out the complete series of reactions from a cold charge 50 to a finished product in a very short interval of time, there is little opportunity for the sodium cyanamid produced to decompose after its formation, before it attains the temperature necessary for a ready combination with the free carbon of the lime nitrogen. I can even avoid this slight chance for decomposition in such a rapidly operating furnace by the addition of carbon in an immediately active form or preferably by the addition of calcium carbid. I can thus take advantage of the large quantity of carbon present in the lime nitrogen for producing a bulk of the cyanid, and have merely to add a very small quantity of

carbon in the form of free carbon such as 65 lamp black, or preferably of calcium carbid. This carbon or carbid addition merely takes care of possible décomposition over the short interval of time during which the charge passes from temperatures just above redness 70 to temperatures above 1200° C. which time interval can be made as short as is deemed advisable by properly proportioning the size of the furnace to the amount of energy put into it.

75 In carrying out my process, I, therefore, find it preferable to use such a form of electric furnace and to so chose the volume of the active zone and the electric energy applied thereto as will make the time of passage from a cold charge to a fused product above 1200° C., as short as possible. It is self-evident that the process can be made continuous by continuously feeding into the top of the furnace a suitable mixture of cold 80 charge material and tapping out the bottom either continuously or at predetermined intervals the melted charge. Also by a suitable predetermined amperage and voltage I 85 can make the temperature gradient from a cold charge to a finished bath as steep as is deemed advisable. In commercially carrying out this process, I have found it advisable to advance the charge at such a speed that it requires only a few minutes after 90 reacting the temperature of redness to reach a temperature above 1200° C.

95 In the process heretofore proposed it has been customary to either place the charge in the furnace already mixed or else to fuse the 100 chlorid in the furnace first and then to add the cyanamid or lime nitrogen and it took all the way from say four to eight hours to complete the reaction. Further, the furnace had to be first charged and the reactions 105 completed before any additional charges were placed therein.

110 My process possesses many advantages over this older batch process, due to the rapid heating which causes the inert carbon to become chemically active; and also due to my continuously operating furnace as opposed to the slower heating in the large 115 batch furnaces, and I obtain a greater efficiency of transformation of cyanamid nitrogen into cyanid nitrogen. This continuous operating furnace is practically self-operating, in that it possesses practically constant electrical conditions in its hearth and is provided with mechanical feed and mechanical tapping, and therefore, needs little or no manual attention. On the other hand, the batch furnace starting with a cold charge and ending up with a molten charge continuously changes its electrical characteristics 120 with consequent demand for personal attention.

125 It is evident that a very important feature

of this invention resides in the fact that I cause the graphitic carbon of the lime nitrogen, or the other carbon present in the charge, to be so suddenly raised in temperature as to render it chemically active at once and to thus cause it to unite with the sodium cyanamid substantially as fast as the latter is formed and therefore prevent the objectionable foaming which has been 5 heretofore experienced, due to the presence of said sodium cyanamid.

Stated in other language, any sodium cyanamid present that is not acted upon by the said graphitic carbon is immediately 10 acted upon by the nascent carbon liberated from the calcium carbide from the charge or it is acted upon by the chemically active carbon which has been added to the charge with the result that no foaming at all takes place, 15 and therefore, there is no tendency, as has been the case in the older processes, for the evolved gases to raise the charge material or lift it from the vicinity of the molten pool 21.

20 It results that said charge material smoothly and evenly works down into the molten pool 21; and as the temperature is quite high, in said pool 21 the material is so fluid as to readily flow along the tap hole 25 and out of the furnace.

It is obvious that those skilled in the art may vary the details of the process without departing from the spirit of the invention, and therefore, I do not wish to be limited 30 to the above disclosure except as may be required by the claims.

What is claimed is:

1. The process of making an alkali metal cyanid which consists in providing a mixture 35 of an alkali metal chlorid, calcium cyanamid and carbon; and raising said carbon to a chemically active temperature before any substantial foaming takes place, substantially as described.

40 2. The process of making sodium cyanid which consists in providing a mixture of sodium chlorid, calcium cyanamid and a substance capable of supplying carbon in the reaction; and raising a portion of the 45 mixture to a temperature above 1100° C. before any substantial foaming takes place, substantially as described.

50 3. The process of making an alkali metal cyanid which consists in providing a mixture 55 of an alkali metal chlorid, and lime nitrogen containing chemically inactive carbon; and raising a portion of said mixture to a temperature sufficient to render said carbon chemically active before any substantial 60 foaming takes place, substantially as described.

4. The continuous process of making an alkali metal cyanid which consists in providing, and continuously feeding a mixture

of an alkali metal chlorid, calcium cyanamid 65 and carbon into the furnace; raising the temperature of said carbon to a chemically active temperature before any substantial foaming takes place; and drawing off the product thus produced as it is 70 formed, substantially as described.

5. The continuous process of making sodium cyanid which consists in continuously feeding into a furnace a mixture of sodium chlorid, calcium cyanamid and calcium carbide; raising the temperature of successive portions of the mixture above 1100° C. before any substantial portion of the sodium cyanamid suffers decomposition; and drawing off the product thus produced as it is 75 80 formed, substantially as described.

6. The process of making an alkali metal cyanid which consists in providing a mixture of an alkali metal chlorid, and lime nitrogen containing chemically inactive carbon; continuously feeding said mixture into a furnace; continuously raising portions of said mixture to a temperature sufficient to render the said carbon chemically active before any substantial foaming takes place; 85 and drawing off successive portions of the product thus produced as fast as they are formed, substantially as described.

7. The process of making sodium cyanid 90 which consists in providing a mixture of calcium cyanamid; sodium chlorid and a substance capable of supplying carbon in the reaction; maintaining a current density through a portion of said mixture sufficient to form the desired cyanid without producing any substantial amount of foaming; and drawing off the molten product as formed, substantially as described.

8. The process of making sodium cyanid 95 which consists in providing a mixture containing substantially equal weights of lime nitrogen and sodium chlorid; and maintaining a current density through a restricted portion of said mixture sufficient to produce the desired cyanid without any substantial 105 foaming while continuing to feed said mixture to and to withdraw said cyanid from the furnace, substantially as described.

9. The process of making sodium cyanid 110 which consists in providing a mixture containing carbon and substantially equal weights of lime nitrogen and sodium chlorid; and maintaining a current density through a restricted portion of said mixture sufficient to produce the desired cyanid 115 without any substantial foaming while continuing to feed said mixture to and to withdraw said cyanid from the furnace, substantially as described.

10. The process of making sodium cyanid 120 which consists in providing a mixture containing combined carbon in the form of calcium carbide and substantially equal weights

of lime nitrogen and sodium chlorid; and maintaining a current density through a restricted portion of said mixture sufficient to produce the desired cyanid without any substantial foaming while continuing to feed said mixture to and to withdraw said cyanid from the furnace, substantially as described.

In testimony whereof I affix my signature in presence of two witnesses.

HORACE FREEMAN.
